UNITED STATES PATENT OFFICE.

FRANCES W. CAPEN, OF READING, MASSACHUSETTS.

KNITTING-BAG.

1,286,225.

Specification of Letters Patent. Patented Dec. 3, 1918.

Application filed August 5, 1918. Serial No. 248,288.

To all whom it may concern:

Be it known that I, FRANCES W. CAPEN, a citizen of the United States, residing at Reading, in the county of Middlesex and 5 State of Massachusetts, have invented new and useful Improvements in Knitting-Bags, of which the following is a specification.

The object of the invention is to utilize a stiffened mouth portion of a knitting-bag as 10 a means for measuring a knitted fabric, so that the proprietor of the bag may conveniently ascertain at any time the length of the fabric by a linear measure carried by the bag, and thus avoid the inconvenience of 15 using a measure independent of the bag.

The invention consists in the improvements hereinafter described and claimed.

Of the accompanying drawing,—

Figure 1 is a perspective view of a knitting-bag embodying the invention, the mouth of the bag being open;

Fig. 2 is a sectional view of the mouth portion of the bag, the mouth being closed.

A bag embodying the invention includes 25 a flexible body portion 12, having flexible extensions 12^a forming the mouth portion of the bag, stiffening means secured to the outer portions of said extensions, the stiffening means of each extension including a flat 30 elongated stiffening member 14, the inner face of which is offset inwardly from the accompanying extension 12^a, and a measure 13 backed by the inner face of one of said stiffening members and supported thereby 35 at the inner side of said extension, and offset inwardly therefrom, the arrangement being such that the measure is concealed when the bag is closed, and exposed for convenient use when the bag is opened.

40 As here shown, the member 14, which may be of any suitable relatively stiff material, constitutes a part of the stiffening means, said means including a member 14 as an inner member, and an outer stiffening member 45 15, spaced from the inner member 14, as shown by Fig. 2. The members 14 and 15 are connected at their outer edges by a neck 16 forming a part of a strip of fabric cemented to said members and bridging the 50 space between their outer edges, and ligatures 17 which may be formed by strands of sewing thread connecting the end portions of said members and spaced inwardly from the neck 16.

55 The extension 12^a is cemented, or other-

wise secured, to the outer side of the inner member 14, and the measure 13 is secured to the inner side of the member 14, so that both the inner side of the member 14, and the measuring strip are offset inwardly from the 60 extension 12^a. The measure is therefore supported by the member 14 in position for convenient use when the bag is opened, and is protected and concealed when the bag is closed.

65 The members 14 and 15 and the connecting means 16 and 17 are utilized to secure to the bag two flexible cords which are looped to form neck portions 18^a interposed between the members 14 and 15, and loose 70 handle portions 18 adapted to depend from the ends of the members 14 and 15, and lie against the outer side of the bag when not in use, so that when the measure is exposed for use, at the inner side of the outer portion 75 of the bag, it is not obstructed by the accompanying handle portion 18.

75 The measure 13 may be a graduated strip of paper, or other suitable material, cemented to the member 14, or to the facing strip 80 of which the neck 16 is a part. A portion of said strip may be covered by an ornamental facing strip 20, as shown.

I claim:

1. A knitting-bag comprising a flexible 85 body having side extensions forming the mouth portion of the bag, stiffening means secured to the outer portions of said extensions, the stiffening means of each extension including a flat elongated inner stiffening 90 member attached to the inner side of the accompanying extension, and a flat elongated outer stiffening member spaced from said inner member, means being provided for connecting said members, flexible cords 95 looped to form neck portions interposed between said stiffening members, and loose handle portions adapted to depend from the ends of said members and lie against the outer sides of the bag when not in use, and a measuring strip backed by the inner face of one of the said inner stiffening members and supported thereby offset inwardly from the inner side of the accompanying extension, said measure being concealed when the bag is closed, and exposed without obstruction by the accompanying handle portion 100 when the bag is opened.

2. A knitting-bag comprising a flexible 105 body having flexible side extensions forming 110

the mouth portion of the bag, stiffening means associated with the outer portions of said extensions, flexible handles engaged with said stiffened portions and adapted to depend loosely from the ends of said portions at the outer sides of the bag when not in use, and a measure on the inner side of one of said stiffened portions, said measure be-

ing offset inwardly from said stiffened portion and concealed when the bag is closed, 19 and exposed for convenient use without obstruction by the accompanying handle when the bag is opened.

In testimony whereof I have affixed my signature.

FRANCES W. CAPEN.
